UNITED STATES PATENT OFFICE.

OLIVER K. SMITH, OF NEWTON, MASSACHUSETTS, ASSIGNOR TO DEAN AND SHERK CORPORATION, OF BOSTON, MASSACHUSETTS, A CORPORATION OF MICHIGAN.

SUPPORT FOR THREAD-COPS.

1,283,939.

Specification of Letters Patent.

Patented Nov. 5, 1918.

Application filed March 19, 1912. Serial No. 223,277.

To all whom it may concern:

Be it known that I, OLIVER K. SMITH, a citizen of the United States, residing at Newton, in the county of Middlesex and State of Massachusetts, have invented certain Improvements in Supports for Thread-Cops, of which the following description, in connection with the accompanying drawings, is a specification, like reference characters on the drawings indicating like parts in the several figures.

This invention relates to thread-cops of the character used to supply thread to high speed sewing machines and the like. A very common commercial type of cop of this character comprises a cylindrical cop tube or core upon which the thread is wound to form a cop body, the ends of this body being substantially flush with the ends of the cop tube.

As above indicated these cops are extensively used to supply thread to high speed sewing machines, and the usual arrangement is to mount the cop on a stand having a spindle projecting therefrom to center the cop, the thread being led through a guide positioned above the cop so that the cop remains stationary as the thread unwinds from its peripheral surface. During the feeding of the thread from this style of cop coils of thread frequently become loosened and drop down to the bottom of the cop where they are liable to get caught under the lower end of the thread body and thus cause the machine to break the thread. This not only results in delay but also causes a waste of thread. With a view to eliminating this trouble it has been proposed heretofore to secure a disk of felt or similar yielding material to the base of the cop 4 where it will form a permanent part of the cop. This expedient, however, has not proved entirely satisfactory since it produces a cop cop that is very awkward to handle when empty and is exceedingly likely to be broken or badly damaged during shipment.

It will be readily understood by those skilled in this art that a device of this character, in order to satisfy the practical requirements of the trade, should be very cheap to manufacture, should be readily detachable from both the machine and also from the cop, should be capable of holding a cop securely thereon until the thread is completely uncoaxed from the cop tube, and

should be capable of being shipped in a small space and without danger of breakage or damage of any character. To devise a support for a thread cop which will satisfy these requirements constitutes the chief object of the present invention.

The nature of the invention will be readily understood from the following description when read in connection with the accompanying drawings, in which,

Figure 1 is an angular view of a thread cop support embodying the present invention; and

Fig. 2 is a cross sectional view, partly in side elevation, of the device shown in Fig. 1, and showing a thread cop supported thereon.

In the drawings, 2 designates the cop tube or core on which the thread body 3 is wound. The cop supporting device comprises a plug 4 which is slightly tapered, as clearly shown in the drawings, in order to enable it to fit snugly inside the tube 2 and compensate for slight variations in the inside diameters of these tubes. The plug has a central hole 5 formed therethrough to receive the spindle that usually projects from the upper surface of a thread stand. The lower end, or base, of the plug 4 has a peripheral shoulder 6 projecting therefrom and a circular disk 7 rests on this shoulder. Another disk 8 preferably made of felt, rests on the disk 7 and forms a covering therefor, these two disks preferably being glued or cemented together. The disk 7 may be made of stiff cardboard or any other relatively light, stiff sheet material, and both the disk 7 and the covering 8 thereto are made of greater diameter than the thread body so that the marginal portions of these members will project beyond the peripheral surface of the thread body at all times.

In using the device the thread cop 3 is placed on the plug 4 and is pushed down on the plug, in case it happens to fit tightly, until the lower end of the thread body rests firmly in contact with the felt covering 8. If, during the thread feeding operation, coils of thread become loosened and drop down around the base of the cop, as above described, the felt prevents the entrance of these coils under the lower end of the cop and thus eliminates any danger of breaking the thread due to its catching under the thread body. The plug 4 may be conven-

iently made of wood and the disks 7 and 8 merely rest on the shoulder 6 so that they can be removed whenever desired. The device thus can be manufactured very cheaply 5 and the disks and plugs can be shipped in separate packages, so that they will require very little shipping space and can easily be protected against breakage. When the machine operator wishes to change cops she 10 merely pulls one cop body or tube (in case the thread has been exhausted) off the plug 4 and places a new cop thereon. It will thus be seen that the device avoids the above described difficulties which have been experi- 15 enced in using former constructions while possessing the advantages of such constructions.

Fig. 3 shows at 10 a slightly different form of plug designed to be used instead of the 20 plug 4 under some conditions, as for instance, when the thread stand is not provided with a plate on which the disks 7 and 8 can rest. In this construction, the hole for the spindle extends only part way through 25 the plug so that the plug is supported on the upper end of the spindle. This arrangement may be conveniently used in certain classes of sewing machines in which the spool revolves instead of being held stationary, as in 30 other types to which reference has been made hereinbefore.

What is claimed as new is:

1. A support for a thread cop, comprising a plug constructed to enter the core of a cop 35 and to be removed therefrom, a disk mounted on said plug, a covering of yielding material for said disk, said disk and the covering therefor being positioned to engage the lower end of a cop mounted in an upright 40 position on said plug and means carried by the plug for supporting said disk but ar-

ranged to permit the removal of the disk from the plug.

2. A support for a thread cop, comprising a plug designed to enter the core of the cop 45 and be removed therefrom, said plug having a shoulder at one end thereof, a disk supported on said shoulder, and a covering of yielding material on said disk, said disk and covering being of greater diameter than the 50 cop whereby the marginal portions of these parts will project beyond the peripheral surface of the cop when the cop rests on said covering.

3. A support for a thread cop, comprising 55 a gradually tapered plug having a peripheral shoulder projecting from the base thereof, said plug being designed to be placed in and removed from the core of a thread cop, a disk removably mounted on said shoulder, 60 and a felt covering for said disk, said disk and the covering therefor being of greater diameter than said thread cop whereby their marginal portions will project beyond the peripheral surface of a thread cop positioned 65 on said plug and resting on said covering.

4. A support for a thread cop, comprising 70 a plug constructed to enter the core of a cop and to be removed therefrom, a disk mounted on said plug, a covering of yielding material for said disk, said disk and the covering therefor being positioned to engage the end of a cop mounted on said plug, and means carried by the plug for supporting 75 said disk but arranged to permit the removal of the disk from the plug, said plug having a central bore extending partially therethrough.

In testimony whereof I have signed my name to this specification.

OLIVER K. SMITH.
